UNITED STATES PATENT OFFICE.

PAUL GIRARD, OF LYON, FRANCE.

VELVET OR CARPET LOOM.

1,099,354.

Specification of Letters Patent.

Patented June 9, 1914.

Application filed March 16, 1912. Serial No. 684,239.

To all whom it may concern:

Be it known that I, PAUL GIRARD, a citizen of the Republic of France, residing at Lyon, in the Republic of France, have invented a new and useful Velvet or Carpet Loom, of which the following is a specification.

The longitudinal pile-wires hitherto used in velvet or carpet looms were bodies independent of the healds in the healds.

My invention relates to improvements in such looms, whereby various advantages are obtained.

One improvement consists in a special heddle for the longitudinal pile-wires, which heddle preferably comprises wire healds.

Another improvement consists in so connecting one longitudinal pile-wire at the inner end with every heald in the special heddle, that the pile-wire can be vertically adjusted, after the heddle has been loosened, and secured in any position by merely tightening the heddle.

A third improvement consists in rendering one part of the pile-wire adjoining the wire heald wholly or mostly pliable similar to a thread, so that the rapid vertical motion of the heddle is transmitted to the outer end of the pile-wire merely by shocks.

I will now proceed to describe my invention with reference to the accompanying drawings, in which—

Figure 1 is a vertical longitudinal section through a part of the velvet or carpet loom and diagrammatically shows one longitudinal pile-wire in combination with the special heddle, Fig. 2 is an elevation on an enlarged scale of the inner end of this pile-wire and the middle part of the wire heald of the special heddle, Fig. 3 is an elevation on an enlarged scale of a modified longitudinal pile-wire in combination with its wire heald, intermediate parts being omitted.

Similar characters of reference refer to similar parts throughout the several views.

In Fig. 1 *a* and *b* are the threads of the ground-warp wound off from the beam *B*, the threads passing the mails *a*¹ and *b*¹ of the healds *a*² and *b*². *A* denotes a beam for the pile-warp *f* whose threads pass through the mails *f*¹ in the heald *f*².

t are the wefts of the ground-fabric, *t*¹ the ordinary wefts or wires, *s* the naps formed of the pile-warp *f*. For the sake of clearness the pile-warp *f*, the pile-leaf *f*² and the naps *s* are indicated by dotted lines, so as to

better distinguish them from the other threads and healds.

I provide a special heddle with healds *E* and connect each of its healds with a longitudinal pile-wire *G H*, whose inner part *G G*¹ is slightly inclined and is made pliable similar to a thread, while the outer part *G*¹ *H* is made horizontal, that is parallel with the fabric, and less pliable. This pile directing member consists of a three-armed part or heddle, having the arm *E*, the arm *F*, and the arm *G—H* of peculiar formation. The threads of both the ground-warp *a b* and the pile-warp *f* pass between the healds *E F* of the special heddle and through corresponding spaces of the usual reed (not shown) and each longitudinal pile-wire *G H* passes through a space of such reed.

The outer part *G*¹ *H* of each longitudinal pile-wire may consist of two superposed wires *c*, *d* and a vertical thin strip *e* of sheet metal soldered to and between them, while the inner part *G G*¹ may consist of the two wires *c d* alone, that is of a single wire so doubled at the inner end *G*, as more clearly shown in Fig. 2. Each heald of the special leaf or heddle *E F* may consist of two parallel wires *g g*¹ twisted together as at *g*² *g*³, so as to form a loop providing a space *g*⁴ between the wires *g g*¹, in which space the two wires *c d* engage from opposite sides, as is clearly shown in Fig. 2. Then the two wires *c d* will be clamped between the two wires *g g*¹, in case the leaf or heddle is tightened, so that in this manner the bowed end *G* of the wire *c d* will be maintained in its position relatively to the two wires *g g*¹ during the vertical reciprocating motion of the special leaf *E F*. For altering the position of the bowed end *G* it is only necessary to loosen and again tighten the leaf.

The longitudinal pile wire *G H* is made so thin as to enable them to freely play in the spaces of the guiding reed (not shown) even if the latter is made narrow, so that the pile-wires do not disturb the formation of a shed nor the motion of the shuttle. In certain spaces of the reed the threads of both the ground-warp and the pile-warp move up and down beneath the parts *G G*¹ of the longitudinal pile-wires passing through the said spaces.

During every upward motion of the special leaf or heddle *E F* the inner parts *G G*¹ of the longitudinal pile-wire connected therewith also raise the outer parts *G*¹ *H*.

and thereby raise the ordinary wefts or wires t^1 , the rapid upward motion of the leaf being transmitted to the outer end H by the effect of shocks similar to a transverse wave line of sound oscillation. At the lowest position of the special leaf or heddle the wefts t^1 and consequently also the naps s are quite loose and the loom can be so arranged, that at this moment both the wefts t^1 and the naps s are with the ground-fabric fed forward, so that the longitudinal pile-wires $G H$ are left behind and are not drawn in by the fabric.

The construction of the longitudinal pile wire described above with reference to Figs. 1 and 2, may be modified in that the pile-wire $4, 4^a$ may be made wholly of thin sheet metal, it being a strip with rounded edges. This strip $4, 4^a$ is made wider at the ends than in the intermediate part, as is clearly shown at Fig. 3. The inner end of this longitudinal pile-wire has a hole 3 , in which the two wires g, g^1 of the heald engage from opposite sides as shown. Then in a similar manner to Fig. 2 the inner end G can be easily vertically shifted, after the leaf $E F$ has been loosened, and secured in any position by merely tightening this leaf.

The vertical adjustment of the inner end G of the longitudinal pile-wire of either construction described along the loop $g^2 g^3$ of the heald renders it possible to form the naps from the weft instead of from the warp, so that the pile-warp f in Figs. 1 and 2 can be omitted. The wefts t^1 being then woven into the ground-fabric will by passing over single longitudinal pile-wire or over groups of longitudinal pile-wires form loops, that is the naps. The wefts t^1 of course serve no longer in an auxiliary capacity but form the pile itself.

The new device described above presents the advantage, that no mails and no special fastening devices independent of the healds are required for the longitudinal pile-wires. Furthermore the device presents the advantage, that the inner ends of the longitudinal pile-wires can be easily adjusted in the vertical direction.

The longitudinal pile wires may be varied without departing from the spirit of my invention. The inner part $G G^1$ may be pivotally connected with the outer part $G^1 H$, the essential point being, that the rapid vertical motion of the special leaf $E F$ can be transmitted through the inner part $G G^1$ to the outer end H solely through the effect of shocks.

I claim:

1. A device for looms of the type described, including a pile-directing member and a heddle, a member of said heddle comprising spaced elements adapted to receive there between said pile-directing member, for vertical adjustment. 60

2. A device for looms of the type described, including a pile-directing member, and a harness or heddle, a member of said harness comprising spaced elements adapted to receive there between said pile-directing 65 member, opposed portions of said pile-directing member being passed from opposite sides of said harness-member elements, in applying said pile-directing member to the latter. 70

3. A device for looms of the type described including a pile-directing member, and a heddle, a member of said heddle comprising spaced elements, said pile-directing member embracing a continuous wire bent 80 to form parallel longitudinal portions, said portions being passed between said elements, upon opposite sides thereof, respectively, the resulting connecting arcuate portion between said longitudinal portions serving to 85 prevent casual withdrawal of said pile-directing member from said heddle member. 75

4. A device for looms of the type described, including a pile-directing member, a heddle, a member of said heddle comprising spaced elements adapted to receive there between said pile-directing members, each of said spaced elements being adjustably connected with a pile-directing member to guard against the position thereof being affected by the drawing action of the fabric in the direction in which it is being wound or reeled. 90

5. A device for looms of the type described, including a pile-directing member, a heddle, a member of said heddle comprising spaced elements adapted to receive there between said pile-directing member, said latter member having an aperture in its inner end, adjacent its connection with said heddle member, and means effecting connection with said pile-directing member, through said aperture, for guarding against displacing said member by the drawing action of the fabric in the direction in which it is being wound or reeled. 100
